(57) **CLAIM**

The ornamental design for a setting for a ring, as shown and described.

DESCRIPTION

FIG. 1 is a front elevational view of a setting for a ring showing my new design;

FIG. 2 is a top plan view of the setting for a ring.

FIG. 3 is a right side elevational view of the setting for a ring in which the left side elevational view is a mirror image of the right side shown.

FIG. 4 is a perspective view of a top side of the setting for a ring; and,

FIG. 5 is a perspective view of a bottom side of the setting for a ring.

The broken lines shown in the drawings represent the boundary of the claim.
